CLAIM

The ornamental design for a rim cover, as shown and described.

DESCRIPTION

[FIG. 1 is a front perspective view of a rim cover with wheel showing the new design;]

[FIG. 2 is a front view thereof;]

[FIG. 3 is a rear view thereof;]

[FIG. 4 is a right side view thereof;]

[FIG. 5 is a left side view thereof;]

[FIG. 6 is a top view thereof;]

[FIG. 7 is a bottom view thereof; and]

FIG. 8 is a front perspective view of a rim cover without wheel showing the new design;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The broken line showing of the hub [in FIGS. 3 and 10] and spokes reflects unclaimed subject matter.

1 Claim, 9 Drawing Sheets

Matter enclosed in heavy brackets [ ] appears in the original patent but forms no part of this reissue; matter printed in italics indicates the additions made by reissue.
